Attorneys.

UNITED STATES PATENT OFFICE

2,432,780

SNOW PLOW

Joseph Mader, Chicago, Ill., assignor to Maremont Automotive Products, Inc., Chicago, Ill., a corporation of Illinois

Application June 4, 1946, Serial No. 674,241

2 Claims. (Cl. 37—53)

1

The present invention relates to an improved snow plow and scraper, and aims to provide a construction having substantial rigidity to withstand the rough usage encountered by articles of this character and which may be easily manually operated.

Another object of the invention is to provide a construction which may be adjusted to perform the function of either a scraper or a path clearer.

Another object of the invention is to provide a construction of this character which may be stored or shipped in a collapsed condition and readily opened up for use as occasion requires.

An additional object of the invention is to provide a wheel or roller supporting means for the scraper or plow which substantially adds to the facility with which the device may be utilized.

An important feature of the invention resides in fixedly supporting the wheel or roller in a manner which allows the construction to be collapsed without the wheel constituting an obstruction. Also, the roller supporting means forms a part of the means for allowing the plow to be adjusted for purposes of a scraper or a path clearer.

Referring to the drawings:

Figure 1 is a rear view in perspective of the plow with the handle bar partly broken away, and showing the device arranged to clear a path, and showing the device arranged to clear a path,

Figure 2 is a front perspective view showing the plow similarly arranged to clear a path,

Figure 3 is a sectional view showing the wheel or roller mounting on the handle, and

Figure 4 is a front perspective view of the plow arranged as a scraper.

In Figures 1 and 2 a bar 10 carries at its lower end an integral vertically extending wing support or pintle 11. In some cases the pintle 11 is welded to the end of the bar 10. It will be noted that the bar 10 extends laterally with respect to the pintle and in a substantially horizontal relation thereto. Hingedly or pivotally carried by the pintle 11 are the wings 12 and 13 of the plow or scraper. Each wing carries upper and lower strap iron hinge members 14 and 15 which are secured to the wings, as shown by means of bolts 16, and the curled pintle receiving portions 17 of the strap members 14 are so disposed and received on the wing support 11 that a pair on one wing, for example, the wing 13, is disposed between the other or outer pair of curled pintle receiving portions 18 of the other wing 14 whereby the wings are held on the vertical pintle without danger of displacement, and yet have free swinging movement for adjustment to operative posi-

tion or for collapsing the wings when storing or shipping the plow.

The wings are provided with outwardly bent portions 19 and 20, the lower portions 19 constituting scraper plates and the upper portions 20 constituting guards to prevent the snow from creeping over the wings.

Each of the wings intermediate its body portion and more nearly adjacent the lower edge is provided with a bracket 21 having an opening 22, and the bar 10 is provided remote from the pintle 11 with a bracket 23 extending on opposite sides of the handle to which it is bolted or welded. Spaced openings 24 are provided on each side of the bracket 23.

The bar 10 at substantially the juncture J of its horizontally extending portion 10' and its integral upwardly bent handle portion 10'', e. g., at the lower end of this latter portion, is provided with an opening 25, as shown in Figure 3, through which extends a shaft 26. One end of the shaft is curled into a hook or opening 27 longitudinally spaced on the bar 10 from the bracket 23 and the opposite end 28 forms a bearing or support for the wheel or roller 29. The roller 29 is received on the shaft 28, as shown in Figure 3, and preferably has a ball bearing mounting 30. The roller is supported for rotating movement upon engagement with the ground by the construction described, and is held fixedly in position by reason of the loop or hook 27 constituting a stop on one end of the shaft, and the nut 31 engaging the opposite threaded end 32 of the shaft. A washer 33 is included between the nut 31 and the hub of the wheel, and also between the bar 10 and the adjacent hub portion, as shown in Figure 3.

A pair of link members or rods 35 are provided, as shown in Figure 1, and one link member has one end engaged in the opening 22 of bracket 21 on the wing 12 and the other end engaged in the loop 27 of the shaft 26. The other link member, which is relatively shorter, has one end engaged in the opening 24 of the bracket 23 on the bar, and the other end engaged in the opening 22 of the bracket on the wing 13. The arrangement shown in Figure 1 of the relatively longer and shorter links may be reversed, i. e., with the longer link engaging the bracket on the wing 13, and the shorter link engaging the bracket on the wing 12, according to whether it is desired to adjust the angular relation of the wings in one direction or the other in clearing a path.

55 In Figure 4 I have shown the invention ad-

justed to act as a scraper with the wings in straight line relation, and in this construction both of the links 35 have one end engaged in the opening of a bracket of the respective wings, and their other ends engaged in the openings 24 of the bracket 23 on the bar 10.

It will be observed that to collapse the construction, it is only necessary to remove one end of each link from engagement with one of the openings on the wing or the bar 10, and the construction may be readily opened-up for operation by simply having the links engage in the respective openings, as described in connection with Figures 1 and 4. When collapsed, the wings fold against the bar 10 and the wheel 29 thus becomes lined up with folded wings so that a flat article is presented.

The plow is preferably constructed entirely of metal, and possesses the necessary rigidity to assure a long life. It is preferred to employ the roller 29, although in some cases, it may be substituted by a runner, or entirely eliminated.

The bar 10 supports all of the parts of the construction and at its free end is provided with suitable handle grips 38. If desired, the plow may be attached to a vehicle or operated by a prime mover.

Referring to Figure 2, it is to be noted that there is an opening O between the ends 39 of the outwardly bent bottom scraper portions 19 when the plow is used to clear a path. Such opening is not objectionable, but there are some cases where it is desirable to close the same. Various means may be used to close this opening.

I claim:

1. A snow plow or scraper comprising a bar, wings pivotally mounted on said bar, means connecting the wings to the bar at a point remote from the pivotal mounting, said connecting

means being adjustable to retain the wings in angular or straight line relation to each other and including rods and means on the wings and longitudinally spaced means on the bar for receiving opposite ends of the rods, one of said means on the bar also affording a support for a traction wheel, and a traction wheel carried on said support.

2. A snow plow or scraper comprising a bar, wings pivotally mounted on said bar, means connecting the wings to the bar at a point remote from the pivotal mounting, said connecting means being adjustable to retain the wings in angular or straight line relation to each other and including rods and means on the wings and longitudinally spaced means on the bar for receiving opposite ends of the rods, said wings being foldable into collapsed relation with the bar, one of said means on the bar affording a support for a traction wheel, and a traction wheel carried on said support and disposed in line with the folded relation of the wings whereby when the plow or scraper is collapsed with the wings in folded position a flat article is obtained.
